(57) **CLAIM**

The ornamental design for a camera unit, as shown and described.

DESCRIPTION

FIG. 1 is a bottom, front and right side perspective view of a camera unit;

FIG. 2 is a top, rear and right side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the camera unit in which the design is embodied that form no part of the claimed design. The dash-dot broken lines denote the boundary of the claim and form no part of the claimed design.

1 Claim, 6 Drawing Sheets

FIG. 1

FIG. 2

FIG. 3

FIG. 4

FIG. 5

FIG. 6

FIG. 7

FIG. 8
